UNITED STATES PATENT OFFICE.

ALBERT C. LOOMIS, OF WEST ORANGE, NEW JERSEY.

NEEDLE-CUSHION FOR SPOOLS.

No. 830,087.

Specification of Letters Patent.

Patented Sept. 4, 1906.

Application filed January 11, 1906; Serial No. 295,677.

To all whom it may concern:

Be it known that I, ALBERT C. LOOMIS, a citizen of the United States, residing at West Orange, in the county of Essex and State of New Jersey, have invented certain new and useful Improvements in Needle-Cushions for Spools; and I do hereby declare the following to be a full, clear, and exact description of the invention, such as will enable others skilled in the art to which it appertains to make and use the same; reference being had to the accompanying drawings, and to numerals of reference marked thereon, which form a part of this specification.

The objects of this invention are to provide a needle-cushion for the ends of spools of thread which will provide a more convenient receptacle for the needle and at the same time serve as a polisher for the same and to secure other advantages and results, some of which may be referred to hereinafter in connection with the description of the working parts.

The invention consists in the improved spool for thread, in the needle-cushion for such spools of thread, and in the arrangements and combinations of parts of the same, all substantially as will be hereinafter set forth, and finally embraced in the claim.

Referring to the accompanying drawings, in which like numerals of reference indicate corresponding parts in each of the several figures, Figure 1 is a side view of a spool for thread, having a needle-cushion secured to its end. Fig. 2 is a view of the back of the cushion, showing the means of attachment. Fig. 3 is a section, somewhat enlarged, taken on line x of Fig. 2.

In said drawings, 5 indicates a spool for thread having at its longitudinal axis a hole or boring 6 and at its opposite ends flanges 7, between which the thread is wound.

At either or both ends of the spool can be secured a needle-cushion 8, adapted to receive the needle to be used with the thread

on the spool. This cushion 8 is preferably filled with emery-powder 9, and this serves as a brightener or polisher by means of which any rust or dirt on the needle can be removed to facilitate sewing.

The cushion is provided with a metallic rear plate 10, having three arms 11, more or less, pressed out from the plate 10 and adapted to enter the hole or boring to hold the cushion in fixed position.

On the outer or upper side of said plate 10 is a plate 12, adapted to close the openings made in pressing out the arms or fingers 11, and thus prevent the escape of emery-powder. At the edges of said plate 10 the same is curled upward and inward over the edges of the textile fabric 13, the flange 14 thus formed pressing said fabric down hard against the inner plate and holding the said fabric, plate 12, and also the powder or filling 65 9 in firm and secure position with respect to the rear plate. Thus constructed the parts can be conveniently and securely applied to the spool for the purposes indicated, the resilience of the sheet-metal arms permitting 70 a secure attachment to spools having differences in diameters of the boring, as will be understood.

Having thus described the invention, what I claim as new is—

A cushion for spools comprising a disk, a sheet of fabric, the disk and the sheet of fabric inclosing a filling, and a plate having its marginal rim bent to embrace the edges of the disk and sheet, and having a series of concentric prongs struck up from the plate, the free ends of the prongs being adapted to enter the perforation of a spool.

In testimony that I claim the foregoing I have hereunto set my hand this 6th day of January, 1906.

ALBERT C. LOOMIS.
